UNITED STATES PATENT OFFICE.

ALBERT LESLIE FRANKEBERGER, OF BLOOMINGTON, ILLINOIS.

BANANA HEATER AND RIPENER.

1,232,270.

Specification of Letters Patent.

Patented July 3, 1917.

Application filed May 22, 1916. Serial No. 99,183.

To all whom it may concern:

Be it known that I, ALBERT LESLIE FRANKEBERGER, citizen of the United States, residing at Bloomington, in county of McLean 5 and State of Illinois, have invented certain new and useful Improvements in Banana Heaters and Ripeners, of which the following is a specification.

My invention relates to an improvement 10 in banana heaters and ripeners.

The object is to provide an appliance of the character mentioned, designed and preferably to be suspended from the wall for the discharge and circulation of heated air 15 in the upper part of a room, so that an approximately uniform and equal distribution and circulation of warm air down through the bananas is provided.

It consists in an outer chamber in the 20 lower end of which a heat is generated and through the restricted upper end of which the heated air circulates and from which it is discharged, there being a window at some 25 intermediate point in the neighborhood of the heat generator for radiating the light.

The accompanying drawing is a view in perspective.

A, is a heating chamber, and 1 is a flat, narrow flue which rises therefrom, and is 30 preferably adapted to rest flat against the wall X where it may be held by wall brackets 2.

The upper discharge end 3, preferably 35 curves over from a vertical to a horizontal position, whereby to discharge and circulate the heated air at a point above the top of the bananas, so that the warm or heated air upon dropping will pass over and down through the bananas hung in the room, thus 40 ripening them.

In the enlarged bottom of the heater, there are preferably three ordinary gas-burners 4, 4, arranged centrally of the chamber, which is left entirely open at the bottom, as at 8, 45 in order that the incoming air may circulate freely around the burner, thereby greatly increasing the efficiency of the heater. A door 5 opens into the side of the chamber,

whereby to light the gas jets 4, 4. In the 50 sloping front 6 mica or other transparent windows 7 are provided for lighting the banana room, so that the gas or other jets serve the double purpose of heating and 55 circulating the air, and also of lighting or illuminating the room.

A test of the work of the apparatus has shown that the temperature of the top of the room in which my improved heater has been placed was 74°, while at the location 60 of the lower end of the bunch of bananas, it was 68°, and the floor was 54° Fh. Thus, the cold damp air is taken from the bottom of the room, heated, and then passed up over and discharged upon the top of the bananas. It has been found that one heater 65 of suitable size is required for about one thousand cubic feet of air.

The heater is preferably so placed that the top or upper discharge end 3, is about 18 inches above the top of the bananas, and 70 the bottom of the heater is adapted to be the same height from the floor as the lower end of the bunch of bananas suspended in the room.

Thus, I produce an efficient appliance 75 which has met the requirements of the fire regulations as well as proven satisfactory for the primary purpose for which it was designed.

I claim:

A banana heater and ripener, comprising a chamber entirely open at the bottom thereof and provided with light and heat burners, a door communicating with said chamber and a comparatively thin flat flue extending 85 vertically and having a horizontal discharge opening at its upper end, the front walls sloping from the heating chamber of the flue and having transparent means therein for transmitting light from the burners 90 within the heat chamber, and brackets attached to the vertical flue for fastening the heater upon the side walls of the room intermediate of the floor and ceiling.

In testimony whereof I affix my signature. 95
ALBERT LESLIE FRANKEBERGER.
